[57] CLAIM

The ornamental design for a blade assembly for cutting shears, substantially as shown and described.

DESCRIPTION

FIG. 1 is a side elevation of a blade assembly for cutting shears showing my new design;

FIG. 2 is a view as seen from the side opposite FIG. 1;
FIG. 3 is a top plan view of FIG. 1; and
FIG. 4 is a top plan view of FIG. 2.

The broken line representing the handle is shown for illustrative purposes only.
